UNITED STATES PATENT OFFICE.

TRISTRAM D. BROWN, OF CANANDAIGUA, NEW YORK.

DESIGN FOR A TEA OR COFFEE POT BLANK.

SPECIFICATION forming part of Design No. 25,285, dated March 24, 1896.

Application filed October 5, 1895. Serial No. 564,753. Term of patent 7 years.

To all whom it may concern:

Be it known that I, TRISTRAM D. BROWN, a citizen of the United States, residing at Canandaigua, in the county of Ontario and State 5 of New York, have invented and produced a new and original Design for Tea or Coffee Pot Blanks; and I do hereby declare the following to be a full, clear, and exact description of the same, reference being had to the accompanying drawings, forming a part thereof.

The recess 1 is formed in the blank. Along said recess the blank is transversely thickened, as at 2, the portion at the recess being 15 thicker than the remainder of the blank.

Having described my invention, what I claim as new, and desire to secure by Letters Patent, is—

The design for a tea or coffee pot blank, as 20 shown and described.

In testimony whereof I affix my signature in presence of two witnesses.

TRISTRAM D. BROWN.
